UNITED STATES PATENT OFFICE.

ANNA A. MACINTYRE, OF HARTFORD, CONNECTICUT.

HAIR-HOLDER.

1,370,142.

Specification of Letters Patent.

Patented Mar. 1, 1921.

Application filed December 3, 1920. Serial No. 427,942.

To all whom it may concern:

Be it known that I, ANNA A. MACINTYRE, a citizen of the United States, and a resident of Hartford, in the county of Hartford and 5 State of Connecticut, have invented new and Improved Hair-Holders, of which the following is a specification.

My invention relates to the class of devices used in dressing the hair of a human 10 head, and especially for holding the hair to enable it to be disposed in various forms, and an object of my invention, among others, is to provide a holder of simple and 15 inexpensive construction that shall effectively serve the purpose for which it is intended.

One form of holder embodying my invention and in the construction and use of which the objects herein set out, as well as 20 others, may be attained, is illustrated in the accompanying drawings, in which—

Figure 1 is a plan view of my improved hair holder.

Fig. 2 is an end or edge view of the same, 25 and

Fig. 3 is a side view.

My improved hair holder comprises two loops 5—6, that overlap each other, as shown in Fig. 1, the inner sides 7—8 of each of 30 said loops forming one side of a hair receiving opening 9 of variable size. The loops 5 and 6 are joined on the same side of each loop, the diameters 10—11 of each loop starting from this point of union being located at an angle each to the other, and as 35 indicated in dotted lines in Fig. 1. This construction enables the loops to be closed together to enlarge the size of the opening 9, as illustrated in dotted lines in Fig. 1, it being possible to enlarge this opening to the 40 size of the openings through the loops, which loops are preferably of the same size.

My improved hair holder is preferably composed of wire having any suitable cov-

ering, as a fine thread, and it may be formed 45 from a single piece of wire, or otherwise, as may be preferred. When composed of a single piece of wire the holder is formed by bending such wire of a certain length into the loop form, as shown in Fig. 1, the 50 opposite ends of this piece of wire being wrapped around and secured to the sides of both loops at the central part 12 of the structure, at which point the two loops are joined. In forming the structure the ends 55 of the wire are bent, commencing at the center of the strand in opposite directions, the ends being extended toward each other, said ends being passed backwardly to form the loops and then being secured as above described.

In accordance with the provisions of the patent statutes I have described the principles of operation of my invention, together with the device which I now consider to represent the best embodiment thereof; but I desire to have it understood that the device shown is only illustrative, and that the invention may be carried out by other means.

I claim:

1. A hair holder comprising two loops joined at one side and each partially overlapping the other.

2. A hair holder comprising two loops of 75 substantially the same size joined at one side and partially overlapping one another, the diameters of the loops, starting at the point of union, extending in divergent directions.

3. A hair holder formed from a single piece of wire with the ends extended in curves rounded toward each other to form two loops of substantially the same size joined at one side and each partially overlapping the other.

ANNA A. MACINTYRE.
